UNITED STATES PATENT OFFICE.

NATHAN SCHWARTZ, OF NEW YORK, N. Y.

SEPARATOR.

1,315,163.

Specification of Letters Patent.

Patented Sept. 2, 1919.

Application filed October 8, 1918. Serial No. 257,417.

To all whom it may concern:

Be it known that I, NATHAN SCHWARTZ, a citizen of the United States, and a resident of the city of New York, borough of Manhattan, in the county and State of New York, have invented a new and Improved Separator, of which the following is a full, clear, and exact description.

The object of the invention is to provide a new and improved separator more especially designed for use in respirators, gas masks and similar devices, and arranged to dissolve, neutralize, filter or separate poisonous fumes, smoke, gases or dust contained in the air breathed by the user. Another object is to permit of freeing the air of, at least, two or more poisonous elements contained therein, such, for instance, as carbon dioxid and carbon monoxid. Another object is to permit of conveniently recharging the separator with neutralizing agents whenever deemed necessary.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a perspective view of the separator;

Fig. 2 is an enlarged sectional side elevation of the same; and

Fig. 3 is a plan view of the same with part broken out.

The casing 10 of the separator is made of wood or light metal and is provided with partitions 11 and 12 to divide the interior of the casing into chambers 13, 14 and 15. The bottom 16 of the casing 10 is provided with an inlet opening 17 across which is stretched wire gauze 18 to prevent large solid matter from entering the separator. The partition 11 is provided with an opening 20 across which is stretched wire gauze 21, a large mesh textile fabric 22 such as grit gauze, and a piece of silk 23, the said members 21, 22 and 23 overlying one the other to provide a filtering means. The partition 12 is provided with an opening 25 across which is stretched wire gauze 26. The openings 17 and 25 are located in the upper portions of the bottom 16 and the par-

tition 12 while the opening 20 is located in the lower portion of the partition 11 thus providing a zigzag passage for the air through the chambers 13 and 14. The chamber 15 is an outlet chamber and is provided with an outlet neck 30 connected by a tube 31 or other means with a respirator, gas mask or the like device or contrivance, for use in drawing the air to be inhaled through the separator.

The chamber 13 contains a receptacle 40, preferably made of wire gauze, and filled with charcoal or other filtering material 41, and the said receptacle 40 is provided with a removable cover 42 extending in the top opening of the chamber 13. The cover 42 is normally held in closed position by the bottom 43 of a spring catch 44 attached by a screw 45 to the partition 11. The filling material 41 is charged with a reacting chemical agent for dissolving, neutralizing or separating, at least, one of the poisonous elements contained in the fumes, smoke or gases in the air drawn through the separator. The chamber 14 is filled with an absorbent material 50 such as a sponge or the like saturated with another chemical agent for dissolving, neutralizing or separating another of the poisonous elements contained in the fumes, smoke or gases with which the air may be charged. The upper open end 51 of the chamber 14 is normally closed by a hinged lid or cover 52 held in closed position by a member 53 of the spring catch 44. The sponge 50 is charged with a chemical for dissolving, neutralizing or separating another poisonous element that may be contained in the air passing through the casing. Thus the charcoal 41 may be saturated with a solution of sodium hydrate for neutralizing carbon dioxid that is contained in the air passing through the casing, and the sponge 50 may be saturated with a suitable chemical for neutralizing carbon monoxid that may be in the air and which is not neutralized by the solution of sodium hydrate contained in the charcoal. In practice, the charcoal 41 is preferably in a granular state and any dust from the charcoal and any dust that may be in the air passing through the casing is prevented from passing from the chamber 13 into the chamber 14 by the superimposed layers 21, 22 and 23 above mentioned.

It is understood that by drawing the air through the casing in a zigzag manner it comes in contact with most of the charged

charcoal and the charged sponge to insure a thorough dissolving, precipitating, neutralizing or separating of the poisonous elements contained in the air and hence the 5 user is not liable to inhale any of the poisonous or deleterious matter.

The receptacle 40 containing the charcoal can be readily removed from the chamber 13 for renewal of the charcoal whenever it 10 is desired to do so; also for sterilizing the container when necessary. In a like manner the sponge 50 may be removed from the compartment 14 for cleaning or other purposes or for conveniently replacing it by 15 another sponge or other absorbent material.

Having thus described my invention, I claim as new and desire to secure by Letters Patent:

1. A separator for respirators, gas masks 20 and the like, comprising a receptacle having at least two chambers of which one is provided with an inlet and another is provided with an outlet, the chambers being connected with each other for the passage of 25 air, charged with extraneous matter, from one to the other, one of the chambers containing a wire gauze cage having a removable cover and charged with a filtering material and a neutralizing agent and the 30 other chamber containing an absorbent material charged with another neutralizing agent, the said chamber containing the absorbent material having a cover for removal of the absorbent material and recharging it 35 with a neutralizing agent, and means for holding the covers of the chamber and cage closed.

2. A separator for respirators, gas masks and the like, comprising a casing provided 40 with partitions dividing it into chambers, the partitions being provided with openings arranged out of alinement with each other, and covered with filtering means, the casing being provided with an inlet opening in alinement with the opening of the 45 partition adjacent the end of the casing opposite that having the inlet opening, said

inlet opening being covered with filtering means, the chamber having the inlet opening being charged with a filtering material 5 and a neutralizing agent and the chamber between the partitions with an absorbent material and a neutralizing agent.

3. A separator for respirators, gas masks and the like, comprising a casing having 55 openings in its top and provided with a vertical partition dividing it into chambers, said partition having in its lower portion an opening covered with a separating material, the chambers having inlet and outlet openings respectively in their upper portions and in alinement with each other, one of the chambers containing a filtering material and a neutralizing agent and the other an absorbent material, and closures for the 60 openings in the top of the casing.

4. A separator for respirators, gas masks and the like, comprising a casing having 65 openings in its top and provided with a partition dividing it into chambers and having 70 an opening covered with a separating material, the chambers having inlet and outlet openings respectively in alinement with each other and out of alinement with the opening of the partition, a cage in the chamber having an inlet and containing a filtering material and a neutralizing agent and the chamber having the outlet containing an absorbent material and covers for the chambers, one of the covers also serving as a closure 75 for the cage.

5. In a separator for respirators, gas masks and the like, a casing having two communicating chambers, one for receiving 80 a cage containing a filtering material and the other for containing an absorbent material, the casing having openings leading to the said chambers, a cover for the opening of the chamber containing the absorbent material, a cover for the cage and opening of 85 the chamber containing the same, and a spring catch secured upon the casing and having its ends engaging the said covers.

NATHAN SCHWARTZ.
